UNITED STATES PATENT OFFICE.

JOSEPH H. HALL, OF WESTFIELD, NEW YORK.

IMPROVEMENT IN POCKET-INHALERS.

Specification forming part of Letters Patent No. 146,589, dated January 20, 1874; application filed December 12, 1873.

To all whom it may concern:

Be it known that I, JOSEPH HENRY HALL, of Westfield, in the county of Chautauqua and State of New York, have invented certain Improvements in Pocket-Inhalers, of which the following is a specification:

The invention relates to that class of inhalers which are portable, and are filled with various pungent or medicated ingredients for the use of persons troubled with asthma, catarrh, &c.; and the invention consists in combining, with a hollow spherical elastic ball, a single central combined air-pipe and inhaling-tube, through which the air is drawn in and the medicated vapor expelled by merely pressing the ball, as hereinafter fully explained.

In the drawings, Figure 1 is a sectional elevation; Figs. 2 and 3, variations in construction.

A represents an elastic ball or sphere, made preferably of rubber, and hollow, with a hole at top and bottom for the admission of the combined air-pipe, standard, and inhaling-tube B. This is constructed of a single piece of wood, with shoulders *a a'*, into which the elastic sphere A springs, and holds of itself at top and bottom, as shown. This inhaling-tube has a central air-passage, *b*, which runs from the nozzle *c* down as far as necessary, and has two or more air and vapor holes, *d d*, formed at right angles with the central air-passage *b* inside the ball, and leading thereto, by which, after the air has filled the ball and become medicated by contact with and passing through the compound, it is expelled by a slight pressure on the ball through these holes *d d* out of the

central passage *b* into the nostrils or mouth of the operator or patient. A cover, *f*, will be attached by a string to put on the tube to keep the strength unimpaired.

The compound will be put in the hollow ball around the central tube B, but the tube itself may be made hollow and filled with the compound, having holes in it to admit the air forced in by the action of the ball, as in Fig. 2; or a ball may be filled and a nozzle set in, as in Fig. 3. The ball acts as a pump, sucking in the air as rapidly as it is expelled by merely relaxing the pressure of the hand. It sets tightly in the grooves made by the shoulders *a a'*, and is thus perfectly air-tight.

I am aware that hollow elastic balls have been used in connection with perfume, and for syringes, but never, so far as I am acquainted, as a receptacle for a medicated compound, and in combination with a simple central tube; and such is my invention.

I claim—

The combined air-pipe, inhaling-tube, and standard B, made in one piece, and having the nozzle *c*, air-holes *d d*, central air and vapor passage *b*, and shoulders *a a'*, in combination with the hollow sphere A, containing the medicated compound, all arranged to operate as and for the purpose hereinbefore specified.

In witness whereof I have hereunto signed my name in the presence of two subscribing witnesses.

J. H. HALL.
